UNITED STATES PATENT OFFICE

MARINO GENTILE, OF CHICAGO, ILLINOIS, ASSIGNOR OF ONE-HALF TO SAMUEL W. WEIS, AND ONE-FOURTH TO GEORGE PICK, BOTH OF CHICAGO, ILLINOIS

TRANSPARENT SHEET

No Drawing.

Application filed February 11, 1928. Serial No. 253,794.

This invention relates to transparent sheets such as are used for wrapping food and other products in sanitary packages, and for various other purposes and applications. Wrapping films or sheets of gelatin have heretofore been used to some extent, but owing to the fragile character and hygroscopic nature of this material such films break or tear easily and soon soften and disintegrate, especially in damp climates. Films made of cellulose nitrate, or gun cotton, have also been known, but owing to the high combustibility of this material, it is more or less dangerous to handle.

The object of my present invention is to provide a thin, flexible, and durable tissue which shall be non-porous and impervious to dust and moisture, of low combustibility, highly transparent, cheap to manufacture, and amply strong to serve the purpose of a wrapper, seal, or container for food and other products under all climatic and atmospheric conditions.

In carrying out my invention, I start with a thin film or sheet of a protein substance, such as gelatin, casein or albumen, all of which substances are capable of being prepared in the form of a thin transparent film, and I then coat this film, preferably on both sides, with a solution containing cellulose nitrate as its chief ingredient. This coating solution may be prepared by first dissolving the cellulose nitrate in a suitable solvent such as ethyl acetate, amyl acetate, ether, etc., which yields a thick or viscous product, and then thinning the latter to a freely flowing state by the addition of a suitable amount of alcohol. To this cellulose nitrate solution is then added a non-hygroscopic material which renders the same soft and pliable, when dry, and also causes it to adhere evenly and uniformly to the gelatin or other protein film; the substance which I have found best adapted to this purpose being castor oil. For practical purposes proportions of 40% to 60% of

castor oil, by weight, of the dried coating of cellulose nitrate has proven to be satisfactory.

The coating solution can be applied to the base film or sheet in any suitable way, as by dipping the base sheet in, or drawing it through, a body of the coating solution, or by flowing the latter over, or brushing it on, the base sheet. When the coating or covering has dried, the resultant product is a tough flexible, transparent sheet of greater strength for the same thickness than either gelatin or gun cotton alone, less combustible than ordinary paper, non-porous and impervious to dust, grease and moisture and thus excellently adapted to serve the purpose of a sanitary wrapper or container, especially for food products, medicines, and the like, and low in cost of materials and manufacture. And while I have found that the materials best adapted to serve all the purposes and characteristics of the invention are gelatin for the base film, and cellulose nitrate admixed with castor oil for the coating or covering, I do not limit the invention, in its broadest aspect, to all of these substances, but may employ such equivalents as are adapted to yield a product having the qualities and characteristics hereinabove described.

I claim—

1. An integral transparent wrapping sheet of the character described consisting of a thin film of gelatin as a base, a coating of cellulose nitrate having castor oil incorporated therein applied to each face of said gelatin film, the castor oil functioning as a non-hygroscopic bonding agent and causing the cellulose nitrate coating to become integrally united with the gelatin film on each side thereof, said resultant wrapping sheet being tough, pliable, transparent, moisture, grease and water proof and being adapted to readily conform to the shape of packages and the like without cracking or separating.

2. An integral transparent wrapping sheet

of the character described consisting of a thin protein film as a base, a coating of cellulose nitrate having castor oil incorporated therein applied to each face of said protein film, the castor oil functioning as a non-hygroscopic bonding agent and causing the cellulose nitrate coating to become integrally united with the protein film on each side thereof, said resultant wrapping sheet being tough, pliable, transparent, moisture, grease and water proof and being adapted to readily conform to the shape of packages and the like without cracking or separating.

MARINO GENTILE.
